US00D932648S

(12) **United States Design Patent** (10) Patent No.: **US D932,648 S**
(45) Date of Patent: **** Oct. 5, 2021**

(54) **UROFLOWMETER**(71) Applicant: **ClearTrac Technologies, LLC**,
Elizabethton, TN (US)(72) Inventors: **Brent Laing**, Greenwood Village, CO
(US); **John Green**, Elizabethton, TN
(US); **Paul R. Johnson**, Boulder, CO
(US); **Robert John Smith**, Louisville,
CO (US); **Robert Edwin Schneider**,
Erie, CO (US); **Magnus Hargis**,
Hudson, CO (US); **Elise Geolat Edson**,
Boulder, CO (US); **Elizabeth A. O'Brien**, Louisville, CO (US); **Joseph L. Kapushion**, Westminster, CO (US)(73) Assignee: **CLEARTRAC TECHNOLOGIES, LLC**, Elizabethton, TN (US)(**) Term: **15 Years**(21) Appl. No.: **29/682,876**(22) Filed: **Mar. 8, 2019**(51) LOC (13) Cl. **24-01**

(52) U.S. Cl.

Primary Examiner — Anhdao Doan*(74) Attorney, Agent, or Firm* — Dorsey & Whitney LLP(57) **CLAIM**

The ornamental design for a uroflowmeter, as shown and described.

DESCRIPTION

FIG. 1 shows a front perspective view of a uroflowmeter; FIG. 2 shows a right elevation view of the uroflowmeter of FIG. 1; FIG. 3 shows a left elevation view of the uroflowmeter of FIG. 1; FIG. 4 shows a front elevation view of the uroflowmeter of FIG. 1; FIG. 5 shows a rear elevation view of the uroflowmeter of FIG. 1; FIG. 6 shows a top view of the uroflowmeter of FIG. 1; and, FIG. 7 shows a bottom view of the uroflowmeter of FIG. 1. The broken lines in FIGS. 1-7 illustrate portions of the uroflowmeter that form no part of the claimed design.
